UNITED STATES PATENT OFFICE

HENRY FUCHS, OF CHICAGO, ILLINOIS, ASSIGNOR TO W. H. MINER, INC., OF CHICAGO, ILLINOIS, A CORPORATION OF DELAWARE

SIDE BEARING FOR RAILWAY CARS

Application filed December 5, 1928. Serial No. 323,854.

This invention relates to improvements in side bearings for railway cars.

One object of the invention is to provide a simple and efficient anti-friction side bearing for railway cars provided with means controlled by relative movement of the body and truck bolsters for centering the same.

Another object of the invention is to provide an anti-friction side bearing of the character indicated, including an anti-friction member interposed between the bolsters, which is supported by the truck bolster and is adapted to have rolling contact with both bolsters when under load, together with centering projections on the anti-friction member having constant engagement with actuating means on the body bolster for centering said member through relative movement of the bolsters, wherein the centering projections and actuating means are so designed and arranged as to be in operative engagement, regardless of the extent of separation of the bolsters.

A still further object of the invention is to provide a side bearing for railway cars, interposed between opposed bearing surfaces on the body and truck bolsters and adapted to have rolling contact therewith when under load, wherein the anti-friction element is supported by the truck bolster at all times and is urged to centered position by the action of gravity, and said element and the body bolster are provided with cooperating means for controlling the position of the anti-friction element by relative angular displacement of the bolsters about their pivotal center.

Yet another object of the invention is to provide an anti-friction bearing for railway cars, including a roller interposed between the body and truck bolsters and supported by the bearing surface of the truck bolster, the bearing surface of said bolster being inclined upwardly in opposite directions from the center to urge the roller to centered position

when displaced, the roller having centering lugs working in vertical guideways on the body bolster whereby the movement of the roller is controlled and the roller is positively rotated to centered position by relative angular movement of the bolsters while returning to vertically aligned position after relative angular displacement thereof about their pivotal center.

Another object of the invention is to provide an anti-friction side bearing including a roller element interposed between the body and truck bolsters of a railway car and supported on the truck bolster, wherein the roller and body bolster are provided with interengaging means for rolling the roller to centered position by relative angular movement of the bolsters to vertically aligned position, and the body and truck bolsters are provided with opposed bearing surfaces, each inclined upwardly in opposite directions from the center, the inclined truck bolster surface assisting in the rolling return movement of the roller to accurate centered position and the inclined body bolster bearing surface compensating for the inclination of the truck bolster bearing surface to maintain uniform spacing between the body and truck bolsters during the operation of the device.

Other and further objects of the invention will more clearly appear from the description and claims hereinafter following.

In the drawing forming a part of this specification, Figure 1 is a vertical sectional view, taken parallel to the length of a car through the ends of the body and truck bolsters thereof and showing my improvements in connection therewith, the parts being shown in full lines in the centered position and the roller and top portion of the truck bolster being shown in dotted line position with the roller displaced to one side. Figure 2 is a horizontal sectional view, corresponding substantially to the line 2-2 of Figure 1. And Figure 3 is a vertical sectional view, corresponding

substantially to the line 3—3 of Figure 1. In said drawing 10 designates the bottom portion or flange of the body bolster and 11 the upper portion or flange of the truck bolster. The two bolsters are provided with the usual center bearing about which the bolsters have angular movement with respect to each other.

My improved side bearing comprises broadly a housing A, an anti-friction roller B, and a bottom bearing plate C secured to the top of the truck bolster.

The housing A is of substantially rectangular box-like form, having spaced side walls 12—12, transverse end walls 13—13, and a horizontal top wall 14. The top wall 14 is provided with laterally extending securing lugs 15 by which the housing is fixed to the bottom side of the body bolster 10. As shown in the present instance, the housing is secured by rivets extending through the lugs 15 and the bottom plate of the bolster 10.

The side walls of the housing are offset, as indicated at 16—16, providing vertically disposed guideways having spaced parallel vertical end walls or surfaces 17—17. The guideways open through the bottom of the housing and extend to the top of the same. The top wall 14 of the housing is provided with a convex bearing surface 18 on the under side thereof. As shown, the bearing surface is inclined upwardly in opposite directions from the center thereof, for a purpose hereinafter more fully pointed out.

The bottom bearing plate C is of substantially rectangular shape and is secured at opposite ends by rivets extending through the plate and the top flange of the truck bolster 11. The central portion of the plate is thickened, as most clearly shown in Figure 1, and said thickened portion is provided with a concave upper bearing surface 19. As shown clearly in Figure 1, the bearing surface 19 is inclined upwardly in opposite directions from the center of the same. The curvature of the bearing surface 19 and the bearing surface 18 is such that when the anti-friction roller element is rolled along between the same the distance between the flanges of the body and truck bolsters will remain substantially constant, that is, the body bolster will not be elevated to any appreciable extent with respect to the top of the truck bolster.

The anti-friction element B is in the form of a true cylindrical roller and is at all times supported on the top surface of the bearing plate C. The roller B is provided with centering lugs 20—20 on the opposite sides thereof. The centering lugs are offset with respect to the end faces of the roller and, as clearly shown in Figures 1 and 3, extend above the top of the roller. The centering lugs engage within the guideways 16 respectively and, as most clearly illustrated in Figure 1, each lug is of such a shape as to occupy

substantially the entire space between the vertical end walls or surfaces 17 of the corresponding guideway. Each lug 20 has upwardly diverging bottom edges 21—21 and curved side edges 22—22 directly above the same. The edges 21 and 22 are so shaped that as the roller is displaced to either side of the centered position the opposed portions of the edge 21 at one side of the lug and the edge 22 at the other side of the lug are always in substantial contact with the spaced parallel walls 17—17 of the guideway. By this arrangement the position of the roller is at all times controlled, and especially during the returning movement of the roller when the same is relieved from load. Inasmuch as the bearing surface 19 of the plate C is upwardly inclined in opposite directions from the center, the roller B will be urged to centered position by the action of gravity thereon after the same has been displaced to either side of the centered position.

In assembling my improved side bearing, the roller is passed within the housing through the open bottom thereof, the lugs being passed into the guideways 16—16. In order to prevent loss of the roller during handling and shipment of the bearing, a pair of retaining cotter pins 23—23 are provided. These pins extend through openings near the bottom ends of the walls 17—17 of the guideways, as clearly shown in Figure 1. The cotter pins 23 which retain the roller within the housing do not, however, engage the centering lugs 20 when the bearing is in actual use on the car, the transverse cotter pins 23 being spaced an appreciable distance below the limit of downward movement of the lugs 20 in the slots 16. By locating the cotter pins as pointed out, relative vertical adjustment of the body bolster with respect to the truck bolster is also permitted without in any way interfering with the centering operation of the bearing. In other words, if it is found desirable to increase the distance between the body and truck bolsters and spacing shims are inserted between the parts of the center bearing, the consequent lifting of the body bolster will not in any way affect the position of the roller on the bearing plate of the truck bolster, because the guides in which the centering lugs 20 are disposed are free to move upwardly without disturbing the lugs.

In the operation of my improved side bearing, assuming that the parts are in the position shown in Figure 1, with the roller in centered position, the top portion of the roller will be engaged by the bearing surface 18 when the bolsters approach each other, thus placing the roller B under load.

Upon relative angular displacement of the body and truck bolsters about their pivotal center, the roller will be rolled along between the bearing surfaces 18 and 19 of the bolsters. During this displacement of the roller, the

centering lugs will move downwardly in the guideways 16 and be guided in a vertical path by the spaced parallel end walls of each guideway while the roller is having true rolling movement between the bearing surfaces.

- 5 In Figure 1, the truck bolster 11 is shown in dotted lines displaced to one extreme position and the relative position of the anti-friction roller is also shown in dotted lines in said figure. The relative position of the lugs 20, when the roller is displaced to the dotted line position shown in Figure 1, are also indicated in dotted lines in said figure. With the roller displaced to either side of the centered position and upon removal of the load therefrom by lifting of the body bolster so as to clear the top of the roller, the latter will be urged to roll to centered position by the action of gravity on the same, due to the inclination of the bearing surface of 15 the plate C which is mounted on the truck bolster. Inasmuch as the centering lugs are disposed between the opposed parallel end walls 17 of the guideways, return movement of the roller is not permitted until the bolsters swing relatively to each other back toward the vertically alined position shown in full lines in Figure 1. The return movement of the roller is thus positively controlled by 20 the centering lugs. Upon relative angular movement of the body and truck bolsters toward the vertical centered position shown in Figure 1, the contacting walls 17 will force the lugs to move and thereby rotate the roller back to the centered position shown in said figure.

- In addition to urging the roller B to centered position by the action of gravity, the inclined bearing surface 19 also serves to determine the true centered position of the roller when the same reaches the lowest point of said inclined surface. As will be evident, the centering lugs 20, upon relative angular movement of the bolsters, serve as means to 45 positively center the roller dependent upon the relative positions of the bolsters, and the inclined bearing surface 19 of the truck bolster supplements the centering lugs in the centering operation and prevents accidental 50 sliding of the roller on the bearing surface of the truck bolster.

While I have herein shown and described what I consider the preferred manner of carrying out my invention, the same is merely 55 illustrative and I contemplate all changes and modifications which come within the scope of the claims appended hereto.

I claim:

1. In a side bearing for railway cars, the 60 combination with cooperating body and truck bolsters; of a bearing member mounted on the truck bolster, having an exterior top bearing surface upwardly inclined from the center in opposite directions; a housing secured to the body bolster, said housing hav-

ing spaced end and spaced side walls and an interior bearing surface opposed to said first named bearing surface; and an anti-friction roller interposed between said bearing surfaces and supported at all times entirely on

70 the truck bolster bearing surface and having rolling contact therewith, movement of said roller lengthwise of said bearing surfaces being limited by said end walls of the housing.

2. In a side bearing of the character described, the combination with a housing adapted to be secured to the under side of a body bolster and having a top wall provided with a downwardly, approximately convex surface on the under side thereof, the axis of said surface extending parallel to the length of said bolster and also provided with depending side walls and depending end walls, said side walls being provided with vertical guideways, each presenting opposed parallel vertical guide surfaces; of an anti-friction roller within said housing, said roller having eccentrically disposed centering lugs, each extending into one of said guideways and confined between the vertical guide surfaces of said guideway in all positions of said lugs, said centering lugs being freely movable up and down in said guideways in all positions of the roller; and a complementary bearing member adapted to be secured to 90 the upper side of the truck bolster and provided on the upper side thereof with an approximately concave bearing surface on which said roller is supported at all times, whereby during actuation of the bearing 95 with the roller under load, the distance between the body and truck bolsters will be maintained substantially uniform, and when the roller is free from load said roller will be free of engagement with the first named bearing surface and will return to its centered position under the influence of gravity controlled by said centering lugs and cooperating guideways.

3. In a side bearing, the combination with an upper bearing member adapted to be secured to the body bolster and provided with a bottom bearing surface; of a lower bearing plate adapted to be secured to the truck bolster and provided with a top bearing surface; a roller interposed between said surfaces; interengaging means on said roller and upper bearing member for inducing rolling of said roller on said bearing surface of the lower bearing plate when the roller is free from load and the bolsters are moved relatively to each other about their pivotal centers to effect centering of said roller when the bolsters are brought to vertically alined position, said upper bearing member having 110 the bearing surface on the under side thereof inclined upwardly from each side of the center thereof, said lower bearing plate having its upper surface inclined upwardly from the center on each side, said surfaces being 115 120 125 130

so related that the distance between the bolsters will be maintained uniform during actuation of said bearing while the roller is under load and upon release of the pressure of the roller the latter will be urged to return to normal position under the influence of gravity.

In witness that I claim the foregoing I have hereunto subscribed my name this 3rd day of December, 1928.

HENRY FUCHS.
